ROCKEL ALEXANDER FRITSCH, OF CHICAGO, ILLINOIS, ASSIGNOR TO JOHN LAWRIE,
OF CHICAGO, ILLINOIS

FOUNTAIN PEN

Application filed June 20, 1937. Serial No. 200,280.

This invention aims to provide a fountain pen of the self-filling type which is capable of being filled through the writing end, and which may conveniently be filled with the use of only one hand for the purpose. The invention further aims to improve the details of construction of self-filling fountain pens, increase greatly their proportional capacity and to improve their operation under neglect and abuse. Other objects and advantages of the construction are hereinafter more fully described in connection with the embodiments of the invention shown in the drawings which accompany and form a part of this specification.

In the accompanying drawings:

Fig. 1 is a longitudinal central section of a pen illustrating a preferred embodiment of my invention, showing the piston and barrel in relative position to begin the filling stroke;

Fig. 2 is a view showing a cross-section of the piston on the line 2—2, Fig. 1, looking in the direction of the arrows, and also showing the front end of the barrel, the barrel and piston being in an angular relationship different from that of Fig. 1;

Fig. 3 is a detail sectional view of the rear end of the barrel on a central longitudinal plane perpendicular to the plane of Fig. 1;

Fig. 4 is a longitudinal central section of a pen showing modifications of certain details;

Fig. 5 is a partial longitudinal sectional view illustrating a modified piston construction, and a cap;

Fig. 6 is a sectional view indicating the position of the parts during the filling operation.

The preferred form of my fountain pen (Fig. 1) consists of a barrel 1 free from openings or movable members except at the lower or writing end, said lower end being closed by a piston 2, which carries the writing element and which is held and reciprocably guided in the barrel by a bushing 3 screwed or otherwise secured to the lower end of said

barrel and forming a continuation thereof and finishing neck closure therefor. External screw threads 4 may be provided near the lower end of the barrel to hold a cap (not shown in Fig. 1). Said barrel, as closed by 50 said bushing and piston, constitutes the ink reservoir of the pen. The barrel 1 is preferably of uniform diameter throughout, and free from interior projections or obstructions except for a boss 5 extending inwardly from the upper end, said boss being internally threaded or otherwise prepared for the attachment of an imperforate central axial filling tube 6 extending approximately the length of the barrel, affording a fluid conduit or connection between the piston and the reservoir during the filling process. Said boss 5 is transversely slotted as at 7 to permit flow of ink, air or both ink and air between the reservoir and the tube.

The bushing 3 is externally finished in any conventional form. Internally it consists of a cylindrical passage 8 through the lower portion, and an outward conical taper 9 in the upper part, said taper enlarging to substantially the inside diameter of the barrel at the inner junction of the piston therewith. A straight longitudinal keyway 10 is channeled inside said cylindrical passage to guide an external key 11 on the piston during the filling operation, as hereinafter described.

Said piston, which may be of either integral or built-up construction, consists of two tubular cylindrical end sections, 12 and 13, sized for a sliding fit within the cylindrical bushing passage 8 and within the lower end of the barrel, respectively, and an intermediate tapered section 14 connecting the two. Said section 13 is circumferentially grooved at 13' (Fig. 1), said grooves being adapted 85 to collect ink, thus forming fluid seals between the piston and the barrel. Said tapered section is made to seat firmly with friction gripping effect upon the corresponding internal taper 9 of the bushing, so as to pre- 90

vent relative movement between the piston and barrel while writing and to make an ink-tight closure, the angle between the taper and the axis of the pen being sufficiently acute to accomplish these results, but without undue binding. The lower end of the piston, which projects, when in the writing position, somewhat beyond the end of the bushing, carries the above-mentioned external key or feather 11, the upper end of which terminates a little short of the lower end of the bushing, and is normally out of registry with the corresponding keyway 10.

Internally the piston comprises two longitudinal passages within the sections 12 and 14, the lower being longer than the upper and of lesser diameter. The upper passage, which is within the portion 13, is of enlarged diameter to avoid reduction of the ink capacity of the reservoir. These two internal sections are joined by a flat annular face 15. A plug piece 16, which also constitutes a feeding element, is rigidly fitted into the lower section 12 of the piston, said plug piece supporting a pen point or nib 17 by the extension 18, somewhat flattened on the bottom, preventing the flow of ink except through channels provided for the purpose. These channels comprise a central hole 19 open at the top and terminating in a rounded bottom 20, and a smaller hole 21, slightly more than capillary size, inclining sharply upward, leading into an outer feed duct 22 on the surface of the plug piece beneath the pen point 17. By this sharp change in direction of ink flow between the holes 19 and 21, flooding of the pen point is prevented. The pen point is of conventional form except that the tip of the base end is turned squarely downward, forming a small lug 23 which fits into a corresponding recess in the plug piece 16, thus positively locking the point in place between the piston wall and the plug piece.

The top of the central passage 19 is tapered as at 24 to guide the lower end of the central axial tube 6 into easy entrance when the piston is moved upward, and the relative lengths of the plug piece and the central tube are such that when the piston is in the extended position, for writing, the lower end of the central tube is below the top of the central passage but out of contact with the walls thereof, leaving a restricted opening for the down flow of ink, as shown in Fig. 1.

The central axial tube 6 is surrounded by a coiled spring 25 seated at one end on the lug 5 in the top of the reservoir and at the other end on the annular shoulder 15, the ends 26 and 27 of said spring being turned down into recesses in their respective seats (Fig. 1). The angular relation of the opposite ends of the spring is such that when the piston is so far extended as to free the key 11 from the keyway 10, the piston will be turned rela-

tively to the barrel and to the bushing 3 into a position such that the key will not be in alignment with the keyway (Fig. 2).

A modified form of my invention is shown in Fig. 4, wherein the barrel or casing member 30 is finished into a unitary lower end 32, the upper end being closed by a plug 31. A central axial tube 33 is screwed or otherwise fastened into the inside of the closure plug 31, said tube being imperforate except for an open bottom and a series of holes 34 near the top, permitting the flow of ink and air during filling. In this modification the external form of the piston is the same as shown in Fig. 1, but the internal construction differs in that the lower and upper cylindrical passages 35 and 36 are connected by a restricted orifice 37 through an otherwise solid part 38 which is about the same length as the tapered section. The restriction of said orifice 37 prevents flooding. The lower passage is closed by a solid plug piece 39 having an ink duct 40 on one side whereby ink is fed beneath the pen point 41. In this form of the invention an operating spring 42 surrounds the central tube 33 for only about the lower half of its length, the upper end of the spring being enlarged as at 43, and fastened to the inside of the barrel, and the lower end being fastened to the piston, the relation of the ends being such as to produce the same torsional effect as in the embodiment shown by Fig. 1. A key 44 and keyway 45, of similar construction and effect to members 11 and 10, Fig. 1, are provided.

Fig. 5 illustrates a further modification of piston construction wherein the upper end 46, of the piston, above the taper 47, is made of flexible material, after the manner of a cup leather, held to the lower part 48 by a flanged bushing 49 screwed into the upper end of said lower part. The flexible material is held against the inside of the barrel 50 by a coiled expander spring 51. This form of piston is intended for use with other appropriate elements of the fountain pen assembly such as are shown by Figs. 1 and 4.

Fig. 5 also illustrates a method of preventing the escape of ink between a cap 52 and the body of the pen. A shoulder 54 within the cap, circularly ridged, seats against the front face 55 of the barrel bushing, in such manner that the grooves between the ridges constitute fluid sealing means to prevent leakage of ink. As an alternative to this construction the shoulder within the cap may be smooth and the front end of the barrel bushing grooved, as at 56, Fig. 1.

In all the embodiments of my invention the various component elements may be assembled in any suitable manner, preferably by screw threads or force fits.

It is to be understood that such features as are not specifically described in connection with each of my various modifications

are similar in construction to the corresponding elements in figures which are completely described and that the characteristic features of the several embodiments, where not inconsistent, may be used together or in part modified in various combinations other than those herein shown and described.

To fill my improved pen the piston and barrel are rotated relatively to each other to bring the key 11 into registry with the key-way 10. This may conveniently be done by holding the flattened bottom of the extension 18 (Fig. 1) on the edge of a desk and turning the barrel. The point is then submerged in ink against an unyielding surface as shown in Fig. 6, and the barrel alternately pushed down by hand and allowed to rise by the action of the spring, the length of the stroke being limited sufficiently to keep the key in the keyway. The down stroke reduces the size of the ink chamber, forcing air out through the passage 7 (Fig. 3) or the holes 34 (Fig. 4), through the tube 6 or 33 and the piston passages. The up stroke sucks ink up through the same course. This ink falls into the bottom of the reservoir, whence it cannot escape, except in minute quantities at the beginning of the succeeding down stroke, for the reason that the bottom flow opening is narrowly restricted, and moreover this opening is closed by the beginning of the down stroke. Completion of filling will be indicated by cessation of bubbles from the point, and by increasing resistance to the down-stroke caused by expulsion of ink instead of air. It will be seen, however, that no injury to the pen can result from unnecessary continuation of the pumping process, since this will only cause a continued circulation of ink. After filling, the spring pushes the piston to full extension, disengaging the key from the keyway, and the torsional effect of the spring moves the parts into the relative position of Fig. 2.

When due to dryness at the pen point or other causes, the flow of ink for writing does not readily begin, it may be started by pushing the barrel downward on the piston, the space between the lower end of the bushing 3 and the upper end of the key 11 allowing just sufficient travel for such a priming stroke.

While I have shown and described my invention for use with a pen-point, it will be understood that a stylographic tip, or other writing element, may be substituted therefor, in combination with such features of my invention as are capable of use therewith.

It will be seen from the foregoing that I have invented a pen of simple and durable construction, reliable and efficient in operation, easily and cheaply manufactured, and leak proof by reason of having no operating openings in the top or sides of the barrel.

55 I provide maximum ink capacity in relation

to the external dimensions of the pen by reason of efficient use of the interior of the barrel, for the reasons that there is no sack, that the spring is placed within the reservoir thus avoiding a spring containing chamber which could not contain ink, that the central filling tube is filled when the reservoir is full, and that the hollow piston forms an effective part of the reservoir.

Having described certain preferred embodiments of my invention without restricting myself thereto, what I claim is:

1. A fountain pen comprising a barrel having no opening except at the lower end, a piston fitted for limited reciprocation in said lower end; said barrel having a contracted bore forming a continuation of said lower end, said piston projecting through said bore and being conically tapered along a portion of its length, and said bore being correspondingly tapered to receive said tapered portion of said piston with a firm closing fit.

2. A fountain pen comprising a barrel having no opening except at the lower end, a piston fitted for limited reciprocation in said lower end, a bushing forming a continuation of said lower end, said piston projecting through said bushing, said piston being tapered along a portion of its length, said bushing being correspondingly tapered to receive said tapered portion of said piston with a firm closing and gripping fit.

3. In a fountain pen of the character described, a barrel, a piston mounted for limited reciprocation within said barrel, and adapted to partially project from one end thereof, a key upon said projecting portion, said key being adapted, when said piston is in extended position, to be entirely without said end and removed therefrom by a short space.

4. In a fountain pen of the character described, in combination, a barrel, a piston closing one end thereof and reciprocable and rotatable therein, a keyway in the piston end of said barrel, a key on said piston adapted to travel in said keyway but capable of lying entirely outside thereof, said key adapted when within said keyway to prevent rotation of said piston, said key adapted when without said keyway to narrowly restrict reciprocation of said piston.

5. In a fountain pen characterized by a reciprocable piston in the writing end, in combination, a nib-supporting plug piece constituting a part of said piston and having filling and feeding ink passages therethrough, said passages comprising a central longitudinal passage closed at the lower end, a reduced passage sharply inclined upward from said lower end, and an exterior ink duct, said reduced passage forming an ink channel between said longitudinal passage and said exterior ink duct.

6. In a fountain pen characterized by a

reciprocable piston in the writing end, in combination, a nib-supporting plug piece constituting a part of said piston and having filling and feeding ink passages therethrough, said passages comprising a central longitudinal passage closed at the lower end, a reduced passage inclined upward from said lower end, and an exterior ink duct, said reduced passage forming an ink channel between said longitudinal passage and said exterior ink duct.

7. In a self-filling fountain pen characterized by a reciprocable piston operable through the writing end, means for automatically altering the angular position of said piston from its normal reciprocating position to its writing position, and means for limiting the extent of reciprocation of said piston possible in the writing position.

8. In a fountain pen of the character described, in combination, a barrel, a reciprocable element in one end of said barrel, a writing point in said reciprocable element, a lug at the base of said writing point, a recess in said reciprocable element wherein said lug is adapted to seat, whereby said writing point is positively secured in proper position in said reciprocable element.

9. In a fountain pen, in combination, a casing member, the internal diameter of said casing member being reduced within one end, a tapered portion within said casing member whereby said reduction is accomplished, a piston mounted for limited reciprocation within said reduced end of said casing member, and a tapered portion on said piston adapted to seat firmly upon said tapered portion within said casing member.

10. In a fountain pen of the self-filling type, a barrel, a bushing of less internal diameter than said barrel on the lower end thereof, a reciprocable writing-element-carrying filling member in said barrel, said member comprising a piston formed of a reduced cylindrical lower portion within said bushing, a flexible upper portion within said barrel having an expansion spring therein, a flanged bushing securing said upper to said lower portion, and an externally tapered section connecting said upper and lower portions.

11. In a fountain pen, in combination, a barrel, a reciprocable piston mounted in the lower end of said barrel, a writing element carried by said piston, a longitudinal central filling tube in said barrel, adapted to coact with said piston, and a piston-actuating spring surrounding said central tube.

12. In a fountain pen, in combination, a barrel, a reciprocable piston mounted in the lower end of said barrel, a writing element carried by said piston, a longitudinal central filling tube in said barrel, adapted to coact with said piston, and a piston-actuating spring surrounding said central tube, said

spring bearing at one end upon said piston and at the other upon said barrel, tending to force said piston out of said barrel.

13. In a fountain pen, in combination, a barrel, a piston reciprocably mounted in the lower end of said barrel, said barrel and piston being provided with relative guide elements, said guide elements being capable of disengagement, a spring bearing upon said barrel and upon said piston, and torsionally secured thereto, whereby to relatively rotate said barrel and said piston upon the disengagement of said guide elements.

14. In a fountain pen, in combination, a barrel, a piston reciprocably mounted in the lower end of said barrel, said barrel and piston being provided with relative guide elements, said guide elements being capable of disengagement, a spring having its opposite ends torsionally secured to and bearing upon said barrel and said piston, tending to push said piston out of said barrel and to turn said piston relatively to said barrel, thereby automatically disengaging said guide elements and moving them angularly out of registry.

15. In a self-filling fountain pen, in combination, a barrel, a reciprocable pen-carrying filling member in the lower end of said barrel, a boss within the upper end of said barrel, an axial tube in said barrel secured in said boss and reaching to and adapted for cooperation with said filling member, and slots in said boss providing communication between said tube and said barrel.

16. In a self filling type of fountain pen, in combination, a rigid reservoir open only at its lower end, a self gripping and self releasing pen carrying member with means for its reciprocation in said lower end to fill said reservoir by alternate expulsion of air and suction of ink through said pen carrying member and an inner by pass tube for alternate passage of air and ink between said reservoir and said pen-carrying member.

17. In a self filling type of fountain pen, in combination, a rigid ink reservoir, a self gripping and self releasing combined piston and point carrying element operable through an opening in the lower end of said reservoir and arranged for reciprocation therein so as to fill said reservoir by the alternate expulsion of air and intake of ink through said point carrying element.

18. In a fountain pen of the character described, in combination, a barrel, a reciprocable piston in one end of said barrel comprising a tubular filling and feed element and a plug piece fixed therein, a nib supported between said element and said plug piece, a lug on said nib, a recess in a member of said piston adapted to receive said lug, whereby said nib is positively locked in position in said reciprocable piston.

19. In a fountain pen, in combination, a

reservoir solidly closed except at the ink feeding end, an ink-feeding passage leading therefrom, a device reciprocable therein for filling the reservoir through said ink feeding end, and matching tapered surfaces on said device and on said reservoir adapted to hold said device frictionally, thereby closing said reservoir except for said ink-feeding passage.

5 In testimony whereof, I have signed my name to this specification.
